UNITED STATES PATENT OFFICE.

JOHN S. TOWNSEND, OF HARVEY, ILLINOIS, ASSIGNOR TO WHITING CORPORATION, OF HARVEY, ILLINOIS, A CORPORATION OF ILLINOIS.

SAFELY-CONTROLLED SAND CUTTING AND SCREENING MACHINE.

Application filed April 13, 1921. Serial No. 461,162.

To all whom it may concern:

Be it known that I, JOHN S. TOWNSEND, a citizen of the United States, residing at Harvey, in the county of Cook and State of Illinois, have invented a certain new and useful Improvement in Safely-Controlled Sand Cutting and Screening Machines, of which the following is a specification.

- 10 In the art of cutting, aerating and remixing used molding sand on a foundry floor there are at the present time machines carried by three or more wheels adapted to run over the floor, pick up sand on it, elevate it to a riddle carried by the machine itself, and finally deliver it in rows of prepared sand suitably located on the floor ready for re-use. Such machines are conventionally equipped with chain and bucket 15 conveyor elevators extending in front in the path of travel of the machine to collect all the sand down to a point very close to the floor and convey it up to the riddle high up in the machine. Foundry floors are 20 not as smooth as billiard tables, but are, on the other hand, more or less rough with the result that as the three or four wheeled machine travels over the floor, it, because of irregularity of the floor itself, or because 25 of sand or pieces of iron or other obstructions on the floor, is of necessity forced to rock and sway out of a level plane as its different wheels encounter these obstructions. This rocking and swaying of the machine necessarily correspondingly raises and lowers the working end of the elevator from the floor, and it is therefore necessary to provide a convenient and easily operable means by which the attendant can vary the 30 angularity of the elevator with reference to the machine and keep its collecting end or nose as near as possible at an even level distance above the floor, thus preventing the nose of the elevator plunging into the 35 floor when the forward end of the machine is depressed and preventing its rising to such a height above the floor that an undesirable quantity of sand is left on the floor when the forward end of the machine is 40 unduly elevated or its opposite end is unduly depressed.

The objects of this invention are to equip such a machine with a readily manipulatable mechanism for constantly controlling 45 the angular position of the elevator, to keep

its nose at a proper distance from the floor and to provide a safety release mechanism which will, in case of accident or attendant's neglect, automatically disconnect the control mechanism from the source of power 60 of the machine.

The invention consists in means for attaining the foregoing objects which can be easily and cheaply made, which is very efficient in operation, and is not readily liable to get out of order. More particularly the invention consists in many features and details of construction hereafter more fully set forth in the specification and claims.

Specifically the invention is an improvement upon the complete machine shown in my prior United States application, Serial No. 380,714, filed May 12, 1920 and so much of that machine is shown in these drawings as appears necessary to understand the present invention.

Referring to the drawings in which like numerals represent the same parts throughout the several views,

Figure 1 is a side elevation of such a machine having the mechanism of this invention applied thereto.

Figure 2 is a plan view of the right hand half of Figure 1 taken on the line 2—2 of that figure, the cutter blades 44 being in a different angular position.

Figure 3 is a perspective view of the special clutch control mechanism which enters largely into this invention.

Figure 4 is a plan view largely in section of the clutch and gearing mechanism.

The, for the purposes of this application, conventional machine shown in the drawings, includes front wheels 10, rear wheels 12, a general frame 14—15—16—17—18—19 and 75 a riddle 20. Pivoted at a suitable shaft 22 near the top of the comparatively high machine is an elevator frame mechanism 24 carrying a suitably mounted elevator chain mechanism 26 equipped with buckets 28 of conventional form adapted as the lower or nose end 30 of the elevator enters the sand 36 to scrape the sand from the floor 38 and carry it up to the riddle 20 for handling by it in the manner well known in the art. 100 The nose 30 of the elevator is conventionally equipped with bracket arms 40 which sustain the outer extremities of lower shaft 42 around which the elevator passes. On the end portions of the shaft outside of the ele- 105 110

vator proper are rotatable blades 44 conventionally known as "ironmen" designed and adapted to, without novelty herein, carry sand from the ends of the shaft 42 to the center of the elevator.

The elevator mechanism described is made of metal and is therefore so heavy and cumbersome to swing about the shaft 22 toward and from the body of the machine to cause the nose end 30 of the elevator to always engage and pick up sand from points as close as possible to the floor 38 without the ironmen 44 either cutting into the floor or being an ineffective distance above the floor, for the reasons pointed out in the opening statement that power mechanism is required for the work.

Each side of the elevator frame is provided with a projecting trunnion 46 on which is journaled a generally horizontal push bar 47 extending inside the main frame of the machine where it is provided with an elongated slot 48 thru which passes shaft 50 carrying a pinion 54 meshing with a rack 56 mounted upon and carried by the member 47. When the shaft 50 is rotated the pinions force their adjacent racks 56 to travel horizontally over the pinions, thus reciprocating the push bars 47 and consequently the elevator mechanism. Shaft 50 is selectively rotatable in either direction thru a preferred form of mechanism entering essentially into this invention. On the end of shaft 50, enclosed within a suitable casing 52, is a worm gear 55, meshing with a worm 57 rigid on a horizontal shaft 58. Rotatably mounted on the shaft are a pair of bevel gears 60-62 placed facing each other and meshing with a common bevel gear 64 on a shaft 66 supplied with power from any suitable source as for instance, thru a sprocket chain 68. Obviously the rotation of shaft 68 and gear 64 causes the gears 60 and 62 to rotate continuously in opposite directions.

Reciprocatable along a spline 70 carried by the shaft 58 is a cylindrical clutch member 72 carrying on opposite ends saw shaped clutched teeth 74 and 75 adapted respectively to mesh with corresponding clutch teeth 76 on the side of gear wheel 62 and teeth 78 on the side of gear 60. Clutch member 72 is enclosed and rotatable within a ring 80 loosely fitting in notch 82 provided for it in the clutch body. Projecting from outside the ring are pins or studs 84 engaging a yoke member 86 pivoted at 88 on a suitable stationary point as for instance frame portion 90. The upper end of this yoke is connected to a rod 92 attached to the swinging end of a lever 94 carried by shaft 96 on whose opposite end portion is an operating lever 98 adapted to be selectively locked by the indented portion 100 of a spring catch 102. When lever 98 is in the notch 100 the collar 80 is held in such a position that

neither set of teeth 74 or 75 carried by member 72 is in mesh with the saw teeth on the adjacent bevel gear 60 or 62. When lever 98 is released from notch 100 and swung upward toward the free end of the spring clip 102, teeth 74 on the left hand end of collar 72 are thrown into mesh with teeth 76 on bevel gear 62 with the result that the power of that gear is transmitted to the shaft 58 to rotate it in one direction to move the rod 47 and consequently the elevator in a given direction. When the lever 98 is released from notch 100 and moved downward as viewed in Figure 2, the engagement of teeth 75 on the right hand end of member 72 with teeth 78 is effected with the result that the oppositely rotating gear 60 rotates shaft 58 in the opposite direction, consequently moves the elevator in the opposite direction from that previously described. The spring in clip 102 is sufficiently strong so that under ordinary conditions it will retain lever 94 in either one of the changed positions described and thus cause the shaft 86 to rotate shaft 58 to swing the elevator.

The saw shaped clutch teeth 74-75-76-78 are very important because when properly held thru the operator's keeping his hand on lever 98 or by the action of member 102 as described, there is sufficient frictional engagement between opposite intermeshing teeth to effect the driving operation described, yet the teeth are sufficiently angular to permit them to act as cam faces to slip apart and thus automatically separate the clutch 72 from the adjacent gear should the nose 30 of the elevator catch on the floor or should the operator accidentally allow elevator to swing so far that the gears 54 reach either one of the ends of the slots 48.

Were ordinary square clutch teeth used in place of the saw teeth automatic disengagement of the power would be entirely impossible should anything happen to the elevator.

By the use of this mechanism the operator can by properly manipulating lever 98 affect a very gradual yet sure control of the elevator and yet keep the mechanism protected from accidents which would otherwise inevitably arise.

Having thus described my invention, what I claim as new and desire to secure by Letters Patent, is:

1. In mechanism of the class described, a wheeled vehicle, an elevator mechanism having a working nose near the floor, means for moving the nose of the elevator toward and from the floor, power driven mechanism for operating said elevator moving means and a manually controllable clutch having saw shaped interfitting teeth interposed between said power driven mechanism and the elevator moving means.

2. In mechanism of the class described, a wheeled vehicle, an elevator mechanism hav-

- ing a working nose near the floor, means for moving the nose of the elevator toward and from the floor, power driven mechanism for operating said elevator moving means and a manually controllable reversible clutch having saw shaped interfitting teeth interposed between said power driven mechanism and the elevator moving means.
3. In mechanism of the class described, a wheeled vehicle, an elevator mechanism having a working nose near the floor, means for moving the nose of the elevator toward and from the floor, power driven mechanism for operating said elevator moving means and a manually controllable clutch having interfitting cam faces, automatically separable under excess load interposed between said power driven mechanism and the elevator moving means.
4. In mechanism of the class described, a wheeled vehicle, an elevator mechanism having a working nose near the floor, means for moving the nose of the elevator toward and from the floor, power driven mechanism for operating said elevator moving means and a manually controllable reversible clutch having interfitting cam faces, automatically separable under excess load, interposed between said power driven mechanism and the elevator moving means.
5. In mechanism of the class described, an elevator member having one end located near the floor, and the other end pivoted to a point high above the floor, means for transporting said elevator in that position over the floor, means for moving the elevator backwards and forward in a vertical plane about said pivot, power driven mechanism for operating said elevator moving means and a manually controllable reversible clutch having interfitting cam faces, automatically separable under excess load, interposed between said power driven mechanism and the elevator moving means.
6. In mechanism of the class described, an elevator member having one end located near the floor, and the other end pivoted to a point high above the floor, means for transporting said elevator in that position over the floor, means for moving the elevator backwards and forward in a vertical plane about said pivot, power driven mechanism for operating said elevator moving means and a manually controllable clutch having saw shaped interfitting teeth interposed between said power driven mechanism and the elevator moving means.
7. In mechanism of the class described, an elevator member having one end located near the floor, and the other end pivoted to a point high above the floor, means for transporting said elevator in that position over the floor, means for moving the elevator backwards and forward in a vertical plane about said pivot, power driven mechanism for operating said elevator moving means and a manually controllable clutch having interfitting cam faces, automatically separable under excess load, interposed between said power driven mechanism and the elevator moving means.
8. In mechanism of the class described, an elevator member having one end located near the floor, and the other end pivoted to a point high above the floor, means for transporting said elevator in that position over the floor, means for moving the elevator backwards and forward in a vertical plane about said pivot, power driven mechanism for operating said elevator moving means and a manually controllable reversible clutch having interfitting cam faces, automatically separable under excess load, interposed between said power driven mechanism and the elevator moving means.
9. In mechanism of the class described, the combination with a wheeled vehicle adapted to pass over a foundry floor, an elevator mechanism for collecting material on the foundry floor and carrying it to a point high up in said machine, a pivotal connection between said elevator mechanism and the body located near the top thereof whereby the working or nose end of the elevator swings close to the floor about said point high up in the machine a source of power accessible inside the machine, means operatively connecting said source of power to be elevated including a reversing mechanism whereby the operator may selectively move the elevator in opposite directions and means operable automatically by excessive strain on the elevator moving means for disconnecting the power means.
10. In mechanism of the class described, a vehicle adapted to travel over a foundry floor, an elevator mechanism pivoted at one end to a point high up on the vehicle, having its other end adapted to engage the floor on which the vehicle travels, a rod pivoted to the elevator intermediate of its length, a rack on said rod, a gear meshing with said rack, a shaft driving said gear, a worm wheel on said shaft, a worm carried by another shaft meshing with the worm wheel, a reciprocatable clutch member splined to the last mentioned shaft, saw teeth at angles of 90° on opposite ends of the clutch member, oppositely rotating power members concentric with the shaft at opposite ends of the clutch member carrying saw teeth meshing with the last mentioned saw teeth, and means under the control of the operator for selectively moving the clutch member into engagement with one or the other of the sets of teeth on the rotating power member.
11. In mechanism of the class described, a vehicle for movement over a foundry floor, an inclined elevator almost touching at one end on the floor, and pivoted at the

- other end high up in the machine, a rotatable shaft, means connecting said shaft in such a manner that as it rotates in opposite directions it rocks the elevator about said pivot, a clutch splined to said shaft, saw teeth on opposite ends of said clutch, power driven rotatable wheels moving concentric with said shaft at opposite ends of the clutch member, provided on their faces with saw teeth interfittable with the teeth on the clutch member, and means controlled by the operator for selectively moving the clutch member into engagement with one or the other of the rotatable power members.
12. In mechanism of the class described, a swinging elevator member, power mechanism for selectively moving the elevator in opposite directions, a clutch member for determining which direction the power mechanism shall move the elevator, a hand operated lever 98 for controlling the clutch, and means for selectively locking said lever in neutral position, for the purposes set forth.
13. In mechanism of the class described, 25 a swinging elevator member, power mechanism for selectively moving the elevator in opposite directions, a clutch member for determining which direction the power mechanism shall move the elevator, a hand operated lever 98 for controlling the clutch, and means for selectively locking said lever in neutral position, said locking means consisting of lever 102, of spring metal having a slight recess 100 intermediate of its ends, 30 for the purposes set forth.
- In witness whereof, I have hereunto subscribed my name.

JOHN S. TOWNSEND.
